Samuel Gordon Inventor

By his Attorney
Schuch, 11/1/1

UNITED STATES PATENT OFFICE.

SAMUEL GORDON, OF BROOKLYN, NEW YORK.

AIRCRAFT NOVELTY.

Application filed February 20, 1923. Serial No. 620,142.

To all whom it may concern:

Be it known that I, SAMUEL GORDON, a subject of Russia, residing in the borough of Brooklyn, county of Kings, city and State of New York, have invented a certain new and useful Aircraft Novelty, of which the following is a specification.

This invention relates to toys and novelties, although the principles embodied therein may be applied to fully operative structures of the device which it simulates. The invention has for its principal object the provision of an attractive and novel toy for children, designed especially to hold the attention and sustain the interest throughout the life of the toy.

The invention is applied particularly to a toy which simulates an aircraft structure, some of the principles of which will be found advantageous in the full-sized aircraft.

It is a further object of this invention to provide a device having the properties and characteristics hereinbefore mentioned, and which is at the same time inexpensive and extremely easy to manufacture.

A further object of the invention is the provision of a toy of the type described, which can be readily collapsed so as to occupy a minimum of space and thus facilitate its shipment and the carrying of large quantities thereof within a comparatively small container.

Further, this invention has for its object the provision of a collapsible toy which is nevertheless simple and easy to set up even by children themselves, with the aid of a few simple directions.

More particularly, this invention provides a device comprising essentially an expandable member, such as a balloon, and wings and struts adapted to maintain the device in the air. The parts are so positioned that the balloon in an expanded position supplies in itself the tension necessary to maintain it against movement in a position between the wings and the struts.

Further, this invention has for its object the construction of a device as hereinbefore described, composed of materials especially adapted to render the toy effective as an aircraft.

With these and other objects in view, to be more fully set forth hereinafter, the invention consists in the novel construction, combination of elements, and arrangement

of parts which will be exemplified in the operation and construction hereinafter described in the following specification and illustrated in the accompanying drawings, 60 considered together or separately.

The inventive idea involved is capable of receiving a variety of mechanical expressions, some of which, for the purpose of illustration, are shown in the accompanying 65 drawings.

The invention will first be described in connection with the accompanying drawings, illustrating one embodiment of the invention, wherein similar reference characters 70 are used to designate corresponding parts throughout the several views, and then more specifically defined and indicated in the appended claims.

In the accompanying drawings: 75

Fig. 1 is a perspective view of the device embodying my invention.

Fig. 2 is a view of the device in a collapsed position.

Fig. 3 is a detail of modified form of 80 wing.

Referring to the drawings, there is shown an expandible member 10 of flexible, resili- 85 ent material adapted to be expanded by filling it with air, or a gas lighter than air, under pressure. This expandible member may be a balloon of the usual type, elongated as shown. Where a lighter-than-air gas is employed within the balloon, the latter will be capable of rising through the air. 90

For sustaining the balloon in the air, or merely for the purpose of simulating closely a form of air craft, the balloon may be provided with a wing structure of the type familiar in connection with biplanes. This 95 wing structure may comprise an upper plane 11 and a lower plane 12, said planes being connected together and held spaced by a plurality of struts 13, 14. The planes may be provided with slots 15 and the struts 16 may be provided with tenons adapted to fit into said slots. A number of said struts 13 are positioned near the outer ends of the planes while certain other of said struts 14 are positioned adjacent the center of said 100 plane. The distance between the upper and lower planes may be substantially the same as the distance between the struts 14. This distance is slightly less than the diameter of the balloon when the latter is expanded, 105 so that the balloon in its expanded condition may be forced into the space bounded by 110

said struts 14 and the upper and lower planes, and be held frictionally wherever positioned.

- The wing structure may be of flexible material and the mortise and tenon joints formed between the struts and planes may be substantially pivotal connections due to the flexibility of the material. The struts are all arranged substantially parallel and 10 since the connection between said struts and the planes are pivotal, there is formed a substantially parallel linkage between the planes, permitting the entire wing structure to be collapsed so that the planes are brought 15 substantially into contact with each other, as shown in Fig. 2. The struts may be flat strips of material arranged with their planes all parallel to each other so that the pivotal axes between the struts and the 20 planes will also all be parallel. It is obvious, therefore, that the wing structure, when the balloon is withdrawn, may be collapsed to occupy substantially the volume of two layers each the thickness of a plane. This 25 volume is, of course, a minimum, and a large number of such wing structures may be packed within a comparatively small container. The balloons may, of course, be exhausted at will and collapsed by untying a 30 string which closes the open end thereof. If desired, the struts may be removed completely from the planes and handled separately. The planes may then be piled one directly on the other.
- 35 When in the fully set up position, the expanded balloon is inserted in the space between the struts 14 and the upper and lower planes and since the diameter of the balloon is slightly greater than the distance between 40 the planes or the distance between the struts 14 there will be a tendency to disconnect the planes from the tenons of struts 14. To obviate this, there may be provided flexible members such as cords 20, passing around 45 the upper and lower planes adjacent each set of struts 14. The two flexible members may be joined above the upper plane by a cord or handle 22 to facilitate carrying of the set-up device.
- 50 The wing structure may be made of any desired or suitable material. When used as a toy, this material should preferably be of minimum weight. It may, therefore, be made of cardboard or similar material, or if 55 desired the struts may be of more rigid material while the planes are made of lighter material. Thus the planes may be made of parchment paper or they may be in the form of frames (see Fig. 3) each having an outer 60 rim 25 of a more rigid material such as cardboard and an inner portion 26 of lighter material such as tissue paper. The struts are all arranged adjacent to the outer edges of the planes so that in cases where said 65 planes are in the form of frames, the tenons

of the struts will project through the rims composed of the more rigid material.

In accordance with the provisions of the patent statutes, I have described the principle of my invention together with the apparatus which I now consider to represent the best embodiment thereof, but I desire it understood that my invention is not confined to the particular form of apparatus herein shown and described, the same being merely 75 illustrative, and that the invention can be carried out in other ways without departing from the spirit of my invention and, therefore, I claim broadly the right to employ all 80 equivalent instrumentalities coming within the scope of the appended claims, and by means of which the objects of my invention are attained, and the new results accomplished, as herein set forth, as it is obvious 85 that the particular embodiments herein shown and described are only some of many and can be employed to attain these objects and accomplish these results.

Having now described my invention, what I desire to secure by Letters Patent is: 90

1. In a device of the character described, an inflated member, a wing structure, and means whereby said member is frictionally held in said structure.

2. In a device of the character described, a distendible member and a wing structure connected thereto and comprising upper and lower planes and struts connecting said planes, said struts being detachably connected to said planes.

3. In a device of the character described, a distendible member and a wing structure frictionally attached thereto and comprising upper and lower planes and struts connecting said planes, said struts being detachably connected to said planes.

4. In a device of the character described, a wing structure comprising upper and lower planes, and a distendible member frictionally held between said planes.

5. In a device of the character described, a wing structure comprising upper and lower planes, and struts connecting said planes, and an inflated member frictionally held between said planes and between certain of said struts.

6. In a device of the character described, a wing structure comprising upper and lower planes, and an inflated member frictionally held between said planes and positioned substantially centrally of said planes.

7. In a device of the character described, a wing structure comprising upper and lower planes and struts connecting said planes, said struts being positioned adjacent the center of said planes, and an inflated member frictionally held between said planes and between said struts.

8. In a device of the character described, a wing structure comprising upper and

lower planes and struts connecting said planes, certain of said struts being positioned adjacent the center of said planes, and an inflated member frictionally held between said planes and between said struts adjacent the center of said planes.

9. In a device of the character described, a plurality of planes, a plurality of connecting members for said planes, and a distensible member adapted to be inserted between said planes, and when distended to place said connecting members under tension.

10. In a device of the character described, a plurality of parallel planes, a plurality of connecting members secured to the margins of said planes and securing them together, and a distensible member adapted to be inserted between said planes and when distended to place said connecting members under tension.

11. In a device of the character described, a plurality of parallel planes, a plurality of struts connecting said planes together, ligamentary elements encircling said planes, and means for placing said struts and ligamentary elements under tension.

12. In a device of the character described, a pair of parallel planes, connecting members for securing said planes together, and an inflatable member positioned between said planes, adapted, when inflated, to place said connecting members under tension.

13. In a device of the character described, a pair of parallel planes, struts joining the margins of said planes, and an inflatable

member positioned between said planes and adapted, when inflated, to put said struts under tension.

14. In a device of the character described, a pair of parallel planes, struts connecting said planes, ligaments encircling said planes, and an inflatable member positioned between said planes and, when inflated, adapted to place said struts and said ligaments under tension.

15. In a device of the character described, a pair of parallel planes, parallel struts connecting said planes, said struts being of such length and so spaced as to form with said planes a chamber adjacent the longitudinal center of said planes, said chamber having equal, opposite square embrasures, and an inflatable member adapted to be inserted in said chamber and when inflated to place said planes and struts under tension.

16. In a device of the character described, a pair of parallel planes, parallel struts connecting said planes, said struts being of such length and so spaced as to form with said planes a chamber adjacent the longitudinal center of said planes, said chamber having equal, opposite square embrasures, an inflatable, cylindrical balloon adapted to be inserted in said chamber and when inserted to place said planes and said struts under tension, and ligatures encircling said planes and resisting the tension of said balloon.

This specification signed this 17th day of February, 1923.

SAMUEL GORDON.
